HARVEY P. WELLMAN, OF SAN FRANCISCO, CALIFORNIA, ASSIGNOR TO ANDERSON-BARNGEOVER MFG. CO., OF SAN JOSE, CALIFORNIA, A CORPORATION OF CALIFORNIA.

METHOD OF TREATING CANNED GOODS.

Application filed November 24, 1924. Serial No. 751,831.

To all whom it may concern:

Be it known that I, HARVEY P. WELLMAN, a citizen of the United States, residing at the city and county of San Francisco and State of California, have invented certain new and useful Improvements in Methods of Treating Canned Goods, of which the following is a specification.

My invention relates to the canning art, 10 the term canning being here used generically to include the use of any containers, whether strictly cans or other vessels, in which comestibles or other commodities are confined, and in which they are treated for 15 desirable ends and purposes, according to the nature of the goods.

In this art, as now highly developed, the common practice is to pass a continuous procession of filled containers through a treating 20 region in a path of such nature, and for a time, adapted for the desired purpose of the treatment; and to this end elaborate machines, necessarily large and costly, and capable of accurately and without confusion 25 conducting the container procession, have been provided and are universally used.

As an example of such machines, which example will indicate both their nature and the most common form of treatment, 30 "cookers", as they are known in the art, may be mentioned. Due to the fact that a very large proportion of the containers used in canning are cylindrical in cross section and are, therefore, adapted for rolling on 35 their axes, the "cookers" are fashioned to provide for such rolling action of the containers as the procession advances through the treating region, thus insuring a uniform and equitable treatment of their contents.

On account of the many necessary factors which must be combined to render a cooker wholly and universally efficient, it is obvious that the machine must either provide for all 40 these factors, or individual cookers must be supplied to meet as many conditions as possible. Neither of these conditions is practicable, the latter especially on account of cost. But if it be possible to extend the 45 capability of the common type or types of cookers, without change, to additional uses, it is obvious that a decided advance in the 50 art is made.

This, then, is my object, and to this end

my invention consists in the novel method of treating canned goods which I shall now 55 fully describe.

In the following disclosure I shall use such examples as are now more prominently in mind, but my method extends to and embraces other illustrations which will readily 60 occur to those skilled in the canning art.

Canned evaporated milk in general practice is put up in "No. 1, tall" cans and in "baby" cans, about 90% of the output going into No. 1 tall, and the remainder into 65 baby cans. The cooker or sterilizing line of apparatus used is only adapted for the No. 1 tall cans and to install a separate cooker or line for baby cans is not in most plants justified, as it would mean a large 70 outlay. Besides, there is difficulty in handling the baby can, as its diameter is practically equal to its length, making it difficult to handle even in a machine especially designed for it, because of the 75 tendency of a can of that shape to turn around or get askew in the can path and cause trouble.

Other illustrations may be given. There are certain food products which could with 80 advantage be treated by the continuous process, which owing to their nature or due to long established custom, are packed in angular or irregular shaped containers 85 which render it difficult, or practically impossible, to run them through a continuous line, and especially so in such a line in which an individual rolling action of the containers is contemplated. For example, corned beef is canned in a rectangular shaped container larger at one end than at the other, to facilitate the movement 90 of its contents; and asparagus is ordinarily put up in rectangular shaped containers in order to hold it firm and prevent injury 95 to the tender tips of the product. Such products could be advantageously handled in the common types of continuous cookers were it not for the angular shape of the containers.

From the foregoing it will be seen that a marked difference in size and number of the containers, as in the case of evaporated milk, is the factor which makes it economically 100 and mechanically prohibitive to use the 105 types of continuous cookers commonly in-

stalled; and that both size and the departure from cylindrical form, as in the case of the angular containers of corned beef and asparagus, are reasons for not being able to handle these products to advantage in such cookers.

My improvement will now readily be understood. According to my method temporary incasements are provided for the filled containers to be treated. These incasements are of a size and shape adapted to be passed through the treating path of the machine, apparatus or line as commonly installed. Such filled containers as cannot, on account of their size or shape or for other reasons be passed through said path, are placed within the temporary incasements, preferably one container in each incasement; and the incasement so supplied with said containers are run through said path, and when discharged are relieved of their treated containers and used again for like purpose.

This will be quite clear by specific reference to the illustrations hereinbefore given. For example taking first the application of the method in the art of processing milk. As before stated the ordinary No. 1 tall cans, being in much the larger number are run through the treating line in the usual manner, because the path of said line is adapted for them. But when the small proportion of baby cans are to be treated, the temporary incasements contemplated by my method are brought into use. Each incasement is supplied with a baby can, and a continuous procession of incasements so supplied are passed through the path of the line; and as said incasements are adapted in size and shape for said path, they pass through with the same facility as the No. 1 tall cans have passed. When discharged from the line, the baby cans are removed from the incasements and the latter are returned to the head of the line for repeating the operation. Thus the same apparatus can be used without change, saving both time and expense. The incasements are not only of a size to be thus used, but in their best form are curvilinear or cylindrical, commonly the latter, adapting them for rolling on their axes, a feature of well known advantage. In the case of the angular or irregular shaped containers of corned beef and asparagus, the same temporary incasements are used, and in this instance both the desirable results of fitting the treating path and of individual rolling therein are secured.

In order to more fully understand my improvement, I refer to the accompanying drawings.

In these drawings—

Fig. 1 is a perspective view of one of the temporary incasements, showing in dotted lines, a "baby" milk can therein.

Fig. 2 is a perspective view of a temporary incasement showing therein an angular asparagus can.

Fig. 3 is a side elevation indicating diagrammatically a treating line usually employed in the processing of milk, a portion of the preheater effect being broken away in order to show one form or type of can-path usually employed; which path is the same in all the effects.

In Figs. 1 and 2, the numeral 1 indicates a cylindrical open ended shell which serves as the temporary incasement for the cylindrical "baby" milk can 2, indicated in Fig. 1, and for the angular asparagus can 3 indicated in Fig. 2.

In Fig. 3, 4 is the preheater effect; 5 is a sterilizer effect and 6 is a cooler effect.

In each of these effects is a can path through which a continuous procession of the filled containers pass. One form of this can path is indicated in the broken portion of the preheater effect 4, and comprises a rotatable reel 7 of horizontally extending parallel spaced peripheral rails 8, coacting with an encircling helically directed fixed rail 9. The cans are carried by and between the reel rails and are advanced with rolling action by contact with the helically directed rail. This form of can path is now in common use and needs no further description. The same form of path is in the other effects 5 and 6.

10 indicates the can feed to the preheater effect 5. 11 is the can communication between the preheater and the sterilizer 5. 12 is the communication between the sterilizer and the cooler 6. 13 is the discharge from the cooler.

14 indicates a runway to return the temporary incasements from the discharge end of the line to the feed end.

In using this apparatus in the processing of milk the No. 1 tall cans, for which the line is normally adapted are run through as is common. But when the time comes for running the "baby" cans through, each baby can 2 is placed in an incasement 1, as in Fig. 1. The incasement being of a size and shape substantially like the No. 1 tall cans is equally adapted for running through the line. The incasements thus supplied with the baby cans are supplied to the feed 5 and are continuously rolled in procession through all the effect of the line. When discharged, the "baby" cans are removed from the incasements and the latter are passed back in the runway 14 to the feed 5 for reuse.

It will be seen that the same method may be applied to the treating of goods in containers which by reason of their shape are not adapted for the ordinary treating apparatus. Thus, as indicated in Fig. 2, an angular asparagus can will be placed in a

temporary incasement of a form adapted for such apparatus, both as to fit and as to rolling action.

I claim:—

5 1. In the treatment of canned goods involving their continuous passage through a treating path, the method of treating goods in containers unadapted for passage in said path which consists in initially placing said

10 containers in temporary incasements adapted for passage in said path; passing said incasements with their inclosed containers through said path; and removing the containers from the incasements after passing

15 through said path.

2. In the treatment of canned goods involving their continuous passage with rolling action through a treating path, the method of treating goods in containers unadapted for passage in said path, which consists in initially placing said containers in temporary incasements adapted for passage with rolling action in said path; passing said incasements with their inclosed containers through said path; and removing the containers from the incasements after passing through said path.

3. In the treatment of canned goods involving their passage with rolling action through a treating path, the method of treating goods in containers unadapted by reason of shape for passage with rolling action through said path, which consists in initially placing said containers in temporary

35 curvilinear incasements adapted for passage

in said path with rolling action; passing said incasements with their inclosed containers through said path; and removing the containers from the incasements after passing through said path.

4. In the treatment of canned goods involving a continuous procession of individual containers through a treating path, the method of treating goods in containers unadapted for such procession in said path which consists in initially placing said unadapted containers in temporary incasements adapted for such procession in said path; passing said adapted incasements in continuous procession of individuals through said path; and removing the containers from the incasements after passing through said path.

5. In the treatment of canned goods involving a continuous procession of individual and individually rolling containers, through a treating path, the method of treating goods in containers unadapted for such rolling procession in said path which consists in initially placing said unadapted containers in temporary incasements adapted for such rolling procession in said path; passing said adapted incasements in continuous procession of rolling individuals through said path; and removing the containers from the incasements after passing through said path.

In testimony whereof I have signed my name to this specification.

HARVEY P. WELLMAN.
